Apr. 6, 1964. This application Dec. 28, 1967, Ser.
No. 697,279

2 Claims. (Cl. 52—223)

ABSTRACT OF THE DISCLOSURE

An anchorage intended to be embedded in a stressed concrete structure inwardly but adjacent an end thereof, the anchorage being rigid and defining a conical wedge receiving portion intended to receive and secure a stressing tendon and surrounded by an expansion resisting plate from which extends one or more columnar elements which are bonded to the concrete to distribute to the concrete the load exerted by the anchorage.

Summary of the invention

This invention relates to anchorage for post-stressed concrete structures, and is a continuation-in-part of application, Ser. No. 357,547, filed Apr. 6, 1964, now abandoned, for Anchorage for Post-stressed Concrete Structures.

Included in the objects of this invention are:

First, to provide an anchorage which is particularly adapted for use in lightweight concrete.

Second, to provide an anchorage which incorporates an effective means of distributing or dissipating the bearing load to a relatively large volume of the concrete, thereby minimizing local crushing loads and permitting the use of lightweight, low strength concrete in stressed concrete structures.

Third, to provide an anchorage wherein rods extend axially from the anchorage into the concrete and function as columns with the load being dissipated through bond to the concrete by mechanical interlock.

Description of figures

FIGURE 1 is a fragmentary, longitudinal, sectional view of a concrete body, such as a beam or slab, showing a pair of tendons and the anchorage therefor, the tendons being shown in their unstressed condition before removal of the headers between which the concrete is cast.

FIGURE 2 is an enlarged, fragmentary, sectional view taken through 2—2 of FIGURE 1 with the concrete omitted, and showing one of the anchorage and adjacent portions of a tendon.

FIGURE 3 is a further enlarged, sectional view taken through 3—3 of FIGURE 2 showing an anchorage embedded in the surrounding concrete with the tendon shown in its stressed condition and sealed in place.

Specification

The concrete body or structure 1 in which the anchorage is employed may be a beam or slab cast within a suitable form which includes headers 2. Extending between the headers 2 are tendons 3. Each tendon may be a single wire, multiple wire strand, or a more complex cable.

In the casting of a concrete slab, it is customary to place a pair of tendons side by side throughout the major length of the slab and divide the tendons within the end margins of the slab, as shown in FIGURE 1. If the concrete beam or slab is stressed by a post-tensioning process, the tendons 3 are placed in the form before pouring the concrete and are initially, substantially tension-free. It is customary to

2

coat the tendons 3 with a lubricant and cover with a sleeve 4 to permit elongation of the tendons 3 after the concrete has set.

The anchorage is employed to secure the tendons 3 after the tendons have been elongated. The anchorage includes an anchor body 5, preferably formed of a helical coil of heavy wire, and having a cylindrical portion 6 and a conical portion 7. The conical portion 7 receives wedges 8 adapted to grip the tendons 3, as shown in FIGURE 3.

Surrounding the conical portion 7 in the region occupied by the wedges 8 is a plate 9 dimensioned to form a radially rigid constraining means to prevent radial expansion of the conical portion 7 when subjected to the loads imposed by the wedges 8. The plate 9 may be brazed, cemented, or otherwise bonded to the anchor body 5. It is preferred to use a cement or adhesive, such as an epoxy resin, to avoid heating and thus reducing the strength of the anchor body 5. The wire forming the coils of the anchor body is of large diameter and therefore quite stiff so that as used, the anchor body is, essentially, a rigid body, and forms with the permanently attached plate 9, a unitary rigid structure.

Initially, each anchor body 5 receives a longitudinally split rubber plug 10 having a conical portion 11 fitted within the conical portion 7, and an enlarged cylindrical portion 12 covering the large end of the anchor body 5. The anchor body is initially held in place by means of nails 13 inserted through holes provided in the plate 9 and adapted to be driven into the header, as shown in FIGURE 2. The nails serve to press the anchor body against the cylindrical portion of the rubber plug 10 so as to seal that portion of the anchor body 5 which later receives the wedges 8.

It is often desirable to stress beams or slabs formed of lightweight aggregate concrete. Such concrete has low strength. It is therefore essential that the loads imposed by the tendons 3 be distributed or dissipated in the concrete in such a manner as to avoid high unit loads. This is accomplished by means of symmetrically placed load-distributing rods 14 secured to the plate 9 and extending axially into the concrete body essentially parallel with the tendons 3. In the construction illustrated, two such rods are shown for each tendon.

The rods 14 are bonded to the surrounding concrete. While they are indicated as cylindrical, they may be twisted or provided with nodules in the manner of concrete reinforcing rods. The length of the rods 14 is determined by the load imposed by the tendons 3 and the strength of the concrete aggregate.

Sufficient surface is provided to maintain the unit load between the rods 14 and the concrete well below the strength of the concrete. The rods 14 act essentially in the manner of steel columns and are capable of carrying large loads since they are completely supported against bending by the surrounding concrete. The rods 14 avoid local crushing loads which have in the past limited the use of bearing plates for the transmission of loads to lightweight aggregate concrete.

The plates 9 associated with the series of tendons 3 may be employed as a convenient means for locating transversely-extending, reinforcing bars 15. It should be understood, however, that such bars extending transversely to the plates 9 do not perform the function of the rods 14 in transmitting the loads from the tendons 3 to the surrounding concrete.

While a particular embodiment of this invention has been shown and described, it is not intended to limit the same to the exact details of the construction set forth, and it embraces such changes, modifications, and equivalents of the parts and their formation and arrangement as come within the purview of the appended claims.

I claim:

1. In a stressed concrete structure having stressing tendons extending between anchorage zones at the ends of said structure; anchorage means in at least one of said zones and having an end portion of one of said tendons secured therein, said anchorage means comprising:

(a) a unitary rigid means, embedded in said concrete structure inwardly from the adjacent end thereof; said unitary rigid means including an internally conical wedge-receiving element surrounding an end portion of said tendon, a plate surrounding and rigidly secured to said element and extending laterally thereof, and at least one elongated rigid columnar element rigidly fixed at one end to a face of said plate and extending away from said adjacent end generally parallel to but laterally spaced from said tendon in said anchorage zone;

(b) a wedge fitting said wedge-receiving element inwardly of said plate;

5 (c) said columnar element being bonded throughout its length to the concrete of said structure whereby to distribute to the concrete the load exerted by said tendon on said anchorage means.

2. A stressed concrete structure, as defined in claim 1, wherein:

(a) said plate is provided with a plurality of said rigid columnar elements symmetrically arranged about said tendon.
